UNITED STATES PATENT OFFICE

172,771

PHONOGRAPH RECORD HOLDER

Otis J. Terrell and Violet I. Terrell,
Creosote, Wash.

Application December 7, 1953, Serial No. 27,969

Term of patent 14 years

(Cl. D33—10)

To all whom it may concern:

Be it known that Otis J. Terrell and Violet I. Terrell, citizens of the United States, residing at Creosote, Washington, have invented a new, original, and ornamental Design for a Phonograph Record Holder, of which the following is a specification, reference being had to the accompanying drawings, forming a part thereof, in which

We claim:

The ornamental design for a phonograph record holder, as shown.
